UNITED STATES PATENT OFFICE.

PETER DUFFY, OF NEW YORK, N. Y.

DESIGN FOR A TALKING-MACHINE CABINET.

48,670.

Specification for Design.

Patented Mar. 7, 1916.

Application filed January 11, 1916. Serial No. 71,586. Term of patent 7 years.

To all whom it may concern:

Be it known that I, PETER DUFFY, a citizen of the United States, residing at New York, in the county of New York and State of New York, have invented a new, original, and ornamental Design for Talking-Machine Cabinets, of which the following is a specification, reference being had to the accompanying drawing, forming part thereof.

The drawing is a perspective view of a

talking machine cabinet showing my new design.

I claim as my invention:

The ornamental design for a talking machine cabinet, substantially as shown.

Signed at New York, in the county of New York and State of New York, this 23rd day of December, 1915.

PETER DUFFY.
